UNITED STATES PATENT OFFICE

92,248

DESIGN FOR A GLASS PLATE OR ARTICLE OF SIMILAR NATURE

Rodney C. Irwin, Newark, Ohio

Application March 3, 1934, Serial No. 50,933

Term of patent 14 years

To all whom it may concern:

Be it known that I, RODNEY C. IRWIN, a citizen of the United States of America, residing at Newark, in the county of Licking and State of Ohio, have invented a new, original, and ornamental Design for a Glass Plate or Article of Similar Nature, of which the following is the specification, reference being had to the accompanying drawing, forming a part hereof:

Figure 1 is a perspective view of a plate, showing my new design.

Figure 2 is a section taken substantially on line 2—2 of Figure 1.

I claim:

The ornamental design for a glass plate or article of similar nature, as shown.

RODNEY C. IRWIN.
